Patented Dec. 3, 1957

181,601

CHAIR SEAT

George J. Pike, Fife Lake, Mich.

Application June 19, 1956, Serial No. 41,968

Term of patent 14 years

(Cl. D15—8)

Fig. 1.

Figure 1 is a perspective view of a chair seat showing my new design;

Figure 2 is a front elevational view of my chair seat;

Figure 3 is a side elevational view of the seat shown in Figure 2;

Figure 4 is a rear elevational view of the seat shown in Figure 2;

Figure 5 is a top plan view of the seat shown in Figure 3; and

Figure 6 is a bottom plan view of the chair seat.

The dotted line shown in the drawing is for illustrative purposes only.

I claim:

The ornamental design for a chair seat, as shown and described.
